Owen, Owen & Grampian.

UNITED STATES PATENT OFFICE

THOMAS J. MURPHY, OF ASTORIA, NEW YORK,

TRANSFORMER.

Application filed March 23, 1923. Serial No. 627,055.

My invention has for its object to provide an efficient transformer that may be made at a low cost of production. The invention provides structural features where-
 5 by the core member of a shell type trans-
 former may be wound and then secured in position so that the magnetic circuit will not be materially different, as to reluctance, from the magnetic circuit of the ordinary
 10 shell type transformer, where the core of the transformer coils is built up at the same time that the other parts of the shell and core are formed. As is well known, trans-
 formers are formed of laminated magnetic
 15 material and the invention particularly pro-
 vides means for inserting the laminated iron core of the transformer coils in position between the laminated end portions of the shell. The invention also provides other
 20 features and advantages that will appear in the following description and upon examin-
 ation of the drawing.

Structures containing the invention may in their details partake of different forms.
 25 To illustrate a practical application of the invention I have selected a transformer as an example of structures containing the invention and shall describe it hereinafter. The structure selected is illustrated in the
 30 accompanying drawings.

Figure 1 illustrates a shell type of a trans-
 former embodying my invention. Fig. 2
 35 illustrates a section of the transformer taken on the line 5—5 indicated in Fig. 1, and
 illustrates the means used for assembling the transformer.

The transformer shown in the drawing may be used for any purpose in connection with which such transformers are commonly
 40 used. The transformer illustrated is partic-
 ularly useful in connection with electricity rectifying systems, where alternating cur-
 rents are rectified by vibrating reeds. The transformer may be secured to a suitable
 45 base by bolts and a clamping flange or plate to securely hold the transformer in position on the base, the base also being used for supporting a vibrating reed.

The transformer 28 is formed of the usual
 50 laminations, the shell part 32 being first formed. The core 33 is also formed of lam-
 inations that are securely riveted together. The upper and lowermost laminations or
 55 thicker punchings are provided with tongues
 that protrude from the end edges thereof.

Each end of the upper and lower laminations is provided with two pairs of tongues 34 and 35. The coil retaining sheet fibre parts 36 are placed on the ends of the core 33 and the tongues 34 are bent outward so as to engage the fibre retaining parts 36. The coil 37 is then wound upon the core and the core and coil are inserted in the shell 32. In order that this may be done the laminations that form the side of the shell 32 and the laminations of the cores are provided with notches 38 that register and in the building-up of the shell and core form slots extending across the inner surfaces of the sides of the shell and the ends 70 of the core. Keys 39 are inserted in the slots thus formed. The inner edges of the keys 39 protrude from the inside surfaces of the sides of the shell sufficiently to engage in the slots formed in the ends of the core 33 and between the tongues 35. The tongues 35 of one of the outside laminations are bent towards the retaining fibre parts so that the core can pass between the sides of the shell 32. The core 33 having the coil 37 thereon is then forced between the keys 38 into position in the shell 32. The keys 39 operate to slightly spring the sides of the shell and prevent engagement of the ends of the laminations of the core with 85 the side edges of the laminations that form the sides of the shell while the core is being placed in position. This prevents bending or marring of the edges of the laminations and injury to same. When the core and coil 90 are placed in position the lower tongues 35 engage with the sides of the shell. The tongues 35 of the other lamination may be bent down so as to engage the other side or face of the shell 32. The keys 39 may 95 then be withdrawn, which will permit close magnetic contact between the core and the shell. The transformer may then be secured in position on the base 1 in the manner de-
 100 scribed above. The coil will dip into the chamber of the base which will permit connections with the coil to be enclosed.

I claim:

1. A shell type transformer having a laminated shell and a laminated core, the laminations of the sides of the shell having registering notches forming channels ex-
 105 tends across the inside faces of the sides of the shell of the transformer, keys located in the channels and protruding therefrom 110

for engaging the ends of the laminated core.

2. A shell type transformer having a laminated shell and a laminated core, the laminations of the sides of the shell and core having registering notches forming channels extending across the inside faces of the sides of the shell of the transformer, keys located in the channels and protruding therefrom for engaging the ends of the 10 laminated core, plates located on opposite sides of the core and having tongues for engaging the sides of the shell to secure the core in position in the shell.

3. A shell type transformer having a 15 laminated shell and a laminated core, the laminations of the sides of the shell having registering notches forming channels extending across the inside faces of the sides of the shell of the transformer, keys located 20 in the channels and protruding therefrom for engaging the ends of the laminated core.

4. A shell type transformer having a laminated shell and a laminated core, the laminations having registering notches 25 forming channels extending across the faces that juxtapose when the shell and core is assembled, removable keys located in the channels and protruding therefrom for engaging the edges of the laminations to 30 spring the shell and core relative to each other to protect the edges of the laminations during the insertion of the core in the shell.

5. A shell type transformer having a laminated shell and a laminated core, the laminations of the sides of the shell having 35 registering notches forming channels extending across the inside faces of the sides of the shell, removable keys located in the channels and protruding therefrom for engaging the ends of the laminated core. 40

6. A shell type transformer having a laminated shell and a laminated core, the laminations of the core having registering notches at the ends of the core that form 45 channels extending across the ends of the core, removable keys located in the channels and protruding therefrom for engaging the laminations of the shell.

7. A shell type transformer having a laminated shell and a laminated core, the 50 laminations of the sides of the shell and the core having registering notches forming channels extending across the inside faces of the sides of the shell and across the ends of the core, removable keys located in the 55 channels and protruding therefrom to prevent engagement between the ends of the laminations of the core with the laminations of the sides of the shell during the insertion of the core in the shell. 60

In testimony whereof I have hereunto signed my name to this specification.

THOMAS J. MURPHY.
